UNITED STATES PATENT OFFICE

FRIEDRICH LUTZ, OF STUTTGART, GERMANY, ASSIGNOR TO UNION SPECIAL MASCHINENFABRIK, G. M. B. H., OF STUTTGART, GERMANY

LOOPER OPERATING MECHANISM FOR SEWING MACHINES

Application filed February 5, 1929, Serial No. 337,806, and in Germany February 8, 1928.

The invention relates to new and useful improvements in a looper operating mechanism for sewing machines, and more particularly to a mechanism whereby a thread carrying looper beneath the work support is oscillated through devices connected to the needle lever mounted on the overhanging arm of the machine.

An object of the invention is to provide an operating mechanism for the looper which is connected to the needle lever at a point adjacent the connection of the actuating means therefor.

A further object of the invention is to provide a looper operating mechanism of the above character wherein the actuating devices are so constructed as to give a dwell to the looper at the forward end of its stroke.

A further object of the invention is to provide a looper operating mechanism of the above character which is provided with means whereby the extent of the dwell given to the looper at the forward end of its stroke and the degree of acceleration given to the looper at the rear end of its stroke may be varied.

A still further object of the invention is to provide a looper operating mechanism of the above type which is so constructed and arranged that the parts above the work support are substantially housed within the standard and overhanging arm.

In the drawings:

Fig. 1 is a view showing in full lines a needle actuating mechanism and a looper operating mechanism embodying the improvements, and in broken lines the movement of the parts and the frame of the machine.

Fig. 2 is a vertical sectional view through the frame of the machine, the needle lever being sectioned at the point where the looper operating mechanism is connected thereto.

Fig. 3 is a detail showing in plan a part of the needle operating lever, the actuating device therefor, and the ball stud connection for operating the looper.

In the drawings which show one embodiment of the invention, a sewing machine frame is indicated at *y*. This sewing ma-

chine frame is provided with an overhanging arm in which is mounted a needle bar *g* carrying a needle *h*. The main shaft *a* is journaled in suitable bearings in the bed of the machine and is provided with a crank intermediate its ends. A link *b* cooperating with the crank is connected to a ball stud *d* at the end of the needle lever *e*.

The needle lever *e* is fulcrumed at *f* within the overhanging arm and is connected at its other end *x* by means of a link to a lug on the needle bar. Thus it is that when the main shaft is rotated, the needle lever is reciprocated.

Located beneath the work support and cooperating with the needle *h* is a thread carrying looper *i*. The looper is mounted on a carrier *k* pivoted at *l* to a looper support of the usual character.

The present invention is directed particularly to the means for oscillating the looper for causing said thread carrying looper to move into and out of the needle thread loop. The needle lever *e* is a lever of the first order and fulcrumed intermediate its ends. The arm *r* of the needle lever carries the ball stud *d* with which the actuating mechanism for operating the needle lever is connected.

The lever adjacent the ball stud *d* is provided with an enlarged head *w*. This enlarged head of the lever is formed with a T-shaped slot *v*. The slot extends substantially in a direction at right angles to the length of the lever. Adjustably mounted in this T-shaped slot *v* is a T-head *u* which is capable of adjustment in the slot and may be secured in various adjusted positions therein. Mounted on this T-head *u* is a ball stud *s*. A link *q* is provided with a head *t* which cooperates with this ball stud *s*. The other end of the link *q* is connected to a head *t'*. The link *q* has right and left threaded connections with the heads *t* and *t'*, which provides a means for lengthening or shortening the link. A lever arm *p* is carried by a shaft *n* mounted in suitable bearings in the standard of the machine. At the outer end of the lever arm *p* is a ball stud with which the head *t'* cooperates. Also mounted on this shaft *n* is a lever arm *o* which carries a ball stud at its 100

lower end. A link m is provided with a head m' at one end which engages a ball stud on the looper carrier k and it is also provided with a head m'' which engages the ball stud at the lower end of the lever arm o . The link has right and left hand threaded connections with these heads m' and m'' . This provides a means whereby the link may be lengthened and shortened.

10 It will be noted that the needle lever is located within the hollow overhanging arm, the actuating means for the needle lever extends through the hollow standard to its connection with the actuating shaft. The link q and the lever arm p are also located within the hollow arm and hollow standard. The arm o , however, is outside of the standard and extends beneath the cloth plate where it is connected to the link which oscillates the looper.

From the above arrangement of the parts, it will be noted that the entire space beneath the overhanging arm is free from obstruction for the passing of the work which is being stitched. The parts above the cloth plate are all substantially housed within the overhanging arm and hollow standard and the one part that is not within the standard is at one side thereof.

30 The purpose of adjusting the position of the ball stud s on the end of the needle lever is to vary the dwell given to the looper at the forward end of its stroke and the acceleration given to the looper at the rear end of its stroke. The arm r of the needle lever and the link q form a toggle arrangement and the ball stud s connecting these parts moves toward and from a line passing through the fulcrum of the lever and the connection of the link q to the lever arm p .

As shown in Fig. 1 in full lines, the ball stud is very close to this line and the looper is at the forward end of its stroke. In fact, the stud may move past the line and this is for the purpose of giving a dwell to the looper at the forward end of its stroke. In the heavy broken dash line the position of the parts when the looper is at the rear end of its stroke is indicated. It will be noted that the ball stud s at this time is at its farthest distance from the line referred to and the looper will come to the rear end of its stroke and quickly start on its forward movement.

When it is desired to decrease the amount of dwell given to the looper, the ball stud s is adjusted away from this line passing through the fulcrum of the lever and the connection of the link q to the lever arm p . By this adjustment, the ball stud does not approach as near the line when the looper reaches the forward end of its stroke and, therefore, there will be a less dwell given to the looper. It is true that this shifting of the ball stud will vary the oscillating position of the looper, but the link m can be very readily lengthened and thus bring the looper back to its proper oscillating position. The dash-and-dot broken line in Fig. 1 indicates the adjustment just referred to. The ball stud may, of course, be adjusted in the other direction so that when the looper is at the forward end of its stroke the ball stud will pass slightly across the dead center line and thus the dwell given to the looper increased.

From the above it will be apparent that a looper actuating means has been provided which may be connected to the usual two-arm needle actuating lever and the connection may be made to said lever adjacent the driving connection therefor, and thus the parts above the work support for operating the looper substantially housed within the standard carrying the overhanging arm. It will also be apparent that the mechanism is very simple and readily accessible for adjustment. It is noted that when the looper is at the forward end of its stroke, the lever arm o and link m are likewise nearer a dead center line passing through the axis of the shaft n and the connection of the link m to the looper carrier, and this will slow up the movement of the looper.

It is obvious that minor changes in the details of construction may be made without departing from the spirit of the invention as set forth in the appended claims.

Having fully described my invention, what I claim as new and desire to secure by Letters Patent, is:—

1. In a sewing machine the combination of a needle bar, a needle carried thereby, a needle lever pivoted intermediate its ends and connected to said needle bar for reciprocating the same, a driving connection to said needle lever at the end thereof opposite the needle bar, a thread carrying looper cooperating with said needle, an oscillating member, a link connected to said oscillating member and to a ball stud adjacent the actuated end of the needle lever, a link connecting said member to said looper for oscillating the same, and means whereby said ball stud may be adjusted on said needle lever in a direction substantially at right angles to the length of the lever for varying the dwell given to the looper at the forward end of its stroke.

2. In a sewing machine the combination of a needle bar, a needle carried thereby, a needle lever pivoted intermediate its ends and connected to said needle bar for reciprocating the same, a driving connection to said needle lever at the end thereof opposite the needle bar, a looper, a looper carrier therefor, a shaft, lever arms carried by the shaft and projecting therefrom, a link connected to one of said needle lever arms and to a ball stud carried by the actuated end of the needle lever, a link connected to the other lever arm and to the looper carrier for oscillating the

looper, said lever arm connected to the needle lever being disposed so that the ball stud moves toward a dead center line when the looper is moved into the needle thread loop, and means for shifting said ball stud on said needle lever toward and from said dead center line, and means whereby said looper may be positioned for oscillation in substantially the same path for all positions of adjustment of the ball stud.

3. In a sewing machine the combination of a needle bar, a needle carried thereby, a needle lever pivoted intermediate its ends and connected to said needle bar for reciprocating the same, a driving connection to said needle lever at the end thereof opposite the needle bar, a thread carrying looper cooperating with said needle, a looper carrier for said looper, said needle lever at the actuated end thereof having a head provided with a T-shaped slot, a T-shaped member carrying a ball stud adjustable in said slot, said slot being disposed so that the ball stud may be adjusted toward and from the longitudinal axis of the lever, a shaft, a lever arm connected to said shaft, a link connecting said lever arm to the ball stud, a second lever arm connected to said shaft, and a link connecting said last-named lever arm with the looper carrier, said last-named link having an intermediate portion with right and left hand thread connections.

4. In a sewing machine, the combination of a needle bar, a needle carried thereby, a substantially straight needle lever pivoted intermediate its ends and connected to the needle bar for reciprocating the same, actuating means connected to the needle lever at the end thereof opposite the needle bar, a thread carrying looper cooperating with the needle, an oscillating member, a link connecting said oscillating member to the looper, a ball stud adjacent the connection between the needle lever and its actuating means, and a link connecting said ball stud to the oscillating member, said link being adapted to move into substantial alinement with the needle lever when the looper is at the forward end of its stroke.

In testimony whereof, I affix my signature.
FRIEDRICH LUTZ.
